HOLDER FOR ROADWAY PAVEMENT EXPANSION MEANS

Filed Dec. 10, 1930

FIG. 1

FIG. 4

FIG. 5

FIG. 6

INVENTOR
WALTER T. LAMB
BY *A. B. Bowman*
ATTORNEY

UNITED STATES PATENT OFFICE

WALTER T. LAMB, OF ALPINE, CALIFORNIA, ASSIGNOR OF ONE-HALF TO HARRY JOHNSON, OF SAN DIEGO, CALIFORNIA

HOLDER FOR ROADWAY PAVEMENT EXPANSION MEANS

Application filed December 10, 1930. Serial No. 501,269.

My invention relates to holders for roadway pavement expansion means, and the objects of my invention are:

First, to provide a holder of this class which is particularly easy to fasten on the 5 headers along the margins of a strip of roadway;

Second, to provide a device of this class which remains interlocked with the concrete when the header is removed;

10 Third, to provide a holder of this class having extension means associated therewith which facilitate the use of the holder with roadways formed of several strips of concrete pavement, whereby the expansion means of the several strips of concrete pavement may be held in alinement and prevent the formation 15 of webs of concrete between the adjacent ends of said expansion means;

Fourth, to provide a holder of this class which reinforces the margins of the pavement at the ends of the expansion strips;

Fifth, to provide a holder of this class which is formed from a minimum amount of 20 material in a simple and economical manner;

Sixth, to provide a holder of this class which in no wise hinders the function of the expansion means; and

Seventh, to provide a novelly constructed 25 holder of this class which is durable, efficient in its action, and which will not readily deteriorate or get out of order.

With these and other objects in view as will appear hereinafter, my invention consists of 30 certain novel features of construction, combination and arrangement of parts and portions as will be hereinafter described in detail and particularly set forth in the appended claims, reference being had to the accompanying drawing and to the characters of reference thereon, which form a part of this application, in which:

Figure 1 is a fragmentary transverse sectional view of a roadbed, showing the relationship of the pavement expansion means and my holder therewith;

45 Figs. 2 and 3 are perspective views of my holder viewed from opposite sides;

Fig. 4 is a fragmentary sectional view 50 through 4-4 of Fig. 1, illustrating the joints

formed between continuing strips of pavement expansion means;

Fig. 5 is a sectional view thereof through 5-5 of Fig. 4, with parts and portions shown in elevation; and

Fig. 6 is a reduced developed view of my holder.

Similar characters of reference refer to similar parts and portions throughout the several views of the drawing.

The holder is formed from a strip of flat stock of sheet metal, as shown in Fig. 6. The blank 1 from which the holder is constructed is beveled at its ends, forming pointed portions 2.

Equidistant from the ends of the blank and near the central portion thereof, there is cut a pair of slits 3, which extend halfway across the blank, as shown best in Fig. 6. These two slits form therebetween a narrow strip or finger 4. The blank is bent along its longitudinal axis until it has a right angular cross section. The blank is also bent transversely along lines continuing from the slit 3. When thus bent, the holder appears as shown best 70 in Figs. 2 and 3.

When so formed, the holder includes a U-shaped holding portion 5 comprising parallel disposed adjacent side portions 5a, connected together by a narrow cross web 5b, 80 which is a continuation of the strip or finger 4.

The remaining leg of each angular portion of the holder forms an outwardly extending ear or flange 6. The two flanges thus formed 85 are in the same plane. Each flange or ear 6 is provided with one or more small perforations 6a. These perforations are adapted to receive tacks or other easily broken means for fastening the holder along the inside margins of a header H, as shown in Fig. 1 and by dotted lines in Fig. 6.

When thus positioned, the U-shaped or supporting portion 5 of the holder extends outwardly from the header. My holder is particularly adapted for holding the expansion strips used in connection with concrete pavement. Such pavement is laid in strips or units about ten feet wide, one strip at a time. At intervals, this pavement unit is separated 95 100

by expansion strips S. The strips are usually formed of a cheap form of sponge rubber, and extend from the roadbed to just below the surface of the pavement, as shown in Fig. 1. The ends of the expansion strips are inserted in the holders 5, or the expansion strip is first positioned and the holder portion is slipped down over the expansion strips, the pointed portions 2 being driven into the roadbed, as shown in Fig. 1.

10 One or more perforations 5c are provided in the holder portion 5, which are adapted to receive a nail 7 or the like, which is forced through the expansion strip, as shown in Fig. 4. When the concrete is poured, this nail is embedded therein, and forms an anchor which retains the holder in position with sufficient force to allow the header to be lifted upwardly and break the temporary securing means which fastened the ear portions 6 to the header.

15 When used in the manner above described, the strips 4 may extend across the top of the header, as shown in Fig. 3 or may be bent 20 down as shown in Fig. 2. This, as well as the cross portion 5b, prevents concrete from being poured between the ends of the expansion strips and the header.

25 The expansion strips of the second or additional unit strips of pavement are positioned in alinement with the expansion strips of the first pavement unit. In order to so hold the additional expansion strips in alinement with the first positioned expansion strip, a pair of extension plates 8 is provided.

30 These extension plates are of sheet metal and are flat. These plates, two in number, are inserted in the holder portion 5 from the exposed or flanged side thereof, as shown in Fig. 4, so as to extend between the side portions 5a of the holder and the expansion strip supported thereby; these plates being thus held in parallel disposed relation, receive the adjacent end of the additional expansion strip, as shown in Figs. 4 and 5. The extension plates 8 are provided with one or 35 more perforations 8a, which receive nails 7 adapted to retain the expansion strip in position and form an anchor when the concrete is poured.

40 When my holder is used with the extension plates, the strips or fingers 4 are particularly useful. The finger 4 is extended across the upper edge of the expansion strip S, as shown in Fig. 5, so as to prevent a concrete web from forming between the adjacent ends of the two paving strips.

45 It is obvious from the construction as illustrated in the drawing and described in the foregoing specification, that I have provided a holder for paving machines as aimed at and set forth in the objects of the invention, and though I have shown and described a particular construction, combination and arrangement of parts and portions, I do not

wish to be limited to this particular construction, combination and arrangement, but desire to include in the scope of my invention the construction, combination and arrangement substantially as set forth in the appended claims.

Having thus described my invention, what I claim as new and desire to secure by Letters Patent is:

1. In a device of the class described, a pair of relatively fixed parallel disposed supporting members arranged to receive a roadway pavement expansion means therebetween, securing flanges extending in angularly disposed relation with said supporting members and means for fastening said supporting members by means of said flanges to headers.

2. In a device of the class described, a pair of relatively fixed parallel disposed supporting members arranged to receive a roadway pavement expansion means therebetween, securing flanges extending in opposite directions from said supporting members and arranged to fit against the side of a roadway header, and temporary means for fastening said flanges to said roadway header, whereby said expansion projects outwardly from said header.

3. In a device of the class described, a pair of parallel disposed supporting members arranged to receive a roadway pavement expansion means therebetween, securing flanges extending in angularly disposed relation with said supporting members, means for fastening said supporting members by means of said flanges to headers, and extension plates arranged to fit between said supporting members and a first expansion means held thereby, said extension plates forming means for supporting a second expansion means in alined relation with said first expansion means.

4. In a device of the class described, a pair of parallel disposed supporting members arranged to receive a roadway pavement expansion means therebetween, securing flanges extending in opposite directions from said supporting members and arranged to fit against the side of a roadway header, temporary means for fastening said flanges to said roadway header, whereby said expansion projects outwardly from said header, and extension plates arranged to fit between said supporting members and a first expansion means held thereby, said extension plates forming means for supporting a second expansion means in alined relation with said first expansion means.

5. In a device of the class described, a pair of parallel disposed supporting members arranged to receive a roadway pavement expansion means therebetween, securing flanges extending in angularly disposed relation with said supporting members, means for fastening said supporting members by means of

said flanges to headers, and anchor means extending through said supporting members and said expansion means and protruding beyond said supporting members.

5 6. In a device of the class described, a pair of parallel disposed supporting members arranged to receive a roadway pavement expansion means therebetween, securing flanges extending in angularly disposed relation with
 10 said supporting members, means for fastening said supporting members by means of said flanges to headers, extension plates arranged to fit between said supporting members and a first expansion means held thereby, said extension plates forming means for supporting a second expansion means in aligned relation with said first expansion means, and a plurality of anchor means extending through said supporting members
 15 and said extension plates, for locking said expansion means therein, said anchor means protruding beyond said supporting members and said expansion plates.

7. In a device of the class described, a
 20 single piece U-shaped supporting member arranged to receive the end of a roadway pavement expansion means, anchor means for securing said expansion means to said supporting member and for interlocking said supporting member in pavement, and means for temporarily securing said supporting member to headers bordering said pavement.

8. In a device of the class described, a U-shaped supporting member arranged to receive the end of a roadway pavement expansion means, anchor means for securing said expansion means to said supporting member, and for interlocking said supporting member in pavement, and means for temporarily securing said supporting member to headers bordering said pavement, said supporting member being pointed at one end so as to be driven into a roadway.

9. In a device of the class described, a supporting member including leg portions arranged to receive the end margins of a roadway pavement expansion means, and a web portion fixedly connecting the upper ends of said legs, and fitting over the end portions of
 45 said expansion means, and means for temporarily fastening said supporting member to roadway headers.

10. In a device of the class described, a supporting member including leg portions arranged to receive the end margins of a roadway pavement expansion means, and a web portion connecting the upper ends of said legs, and fitting over the end portions of said expansion means, an ear protruding from
 55 the web portion of said supporting member, and extension plates arranged to fit between said leg portions and said expansion means, and receive a second expansion means therebetween, said ear arranged to cover the space
 60 between said extension plates and co-act with
 65

said web portion to prevent entrance of paving material between said first and second expansion means.

11. In a device of the class described, a supporting member including leg portions arranged to receive the end margins of a roadway pavement expansion means, and a web portion connecting the upper ends of said legs and fitting over the end portions of said expansion means, said portions being pointed so as to be driven into a roadway.

12. In a device of the class described, a supporting member including leg portions arranged to receive the end margins of a roadway pavement expansion means, and a web portion connecting the upper ends of said legs, and fitting over the end portions of said expansion means, flanges formed along corresponding margins of said leg portions, and extending in opposite directions, said flanges arranged to fit against a header and be temporarily secured thereto.

In testimony whereof, I have hereunto set my hand at San Diego, California, this 26th day of November, 1930.

WALTER T. LAMB.
